CLOCK CASING

Charles A. McLeod, Oak Park, Ill., assignor to Sunbeam
Corporation, Chicago, Ill., a corporation of Illinois

Filed July 2, 1964, Ser. No. 80,687

Term of patent 14 years

(Cl. D42—7)

FIG. 1 is a front elevational view of a clock casing embodying my new design;

FIG. 2 is a side elevational view thereof when viewed from the left-hand side of FIG. 1;

FIG. 3 is a top plan view thereof;

FIG. 4 is a side elevational view thereof when viewed from the right-hand side of FIG. 1;

FIG. 5 is a sectional view taken along the section line 5-5 of FIG. 1; and

FIG. 6 is a sectional view taken along the section line 6-6 of FIG. 1.

I claim:

The ornamental design for a clock casing, as shown.
